(57)

CLAIMThe ornamental design for light therapy device, as shown
and described.**DESCRIPTION**FIG. 1 is a front perspective view of a light therapy device
showing the new design;

FIG. 2 is a bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom view plan thereof.

The even-length broken lines shown in the drawings illus-
trate portions of the light therapy device that form no part of
the claimed design. The broken lines of uneven length
illustrate the boundary of the claimed design and form no
part thereof.**1 Claim, 8 Drawing Sheets**(56)
